TOY

Marion Ross, Louisville, Ky.

Application March 29, 1939, Serial No. 264,813

1 Claim. (Cl. 46—156)

This invention relates to improvements in toys, but as will presently be seen, the device does not always necessarily comprise a toy. The socalled toy may be used as a mantel ornament, 5 as a novelty and an item of fancy work, in fact is adaptable to quite a number of kindred uses as will suggest themselves to persons skilled in this particular art.

The article is herein depicted as a poodle-dog, 10 one characteristic of which is long flowing hair. The principle underlying this simulation is capable of extension to the making of animals other than this particular type of dog and in the copying of other living natural objects. With 15 this preamble in mind the purposes of the invention are as follow:

First, to provide an article which is adaptable to use as a toy, display novelty or the like, having as one of its outstanding characteristics the 20 use of shredded paper, Cellophane or any one of a variety of fabrics for the simulation of an object in nature.

Second, to provide an article of the character described which consists primarily of a suitable, 25 armature, a more or less rigid foundation on the armature in most instances, and a shredded paper or similar covering which is capable of being fluffed up to represent fur or the like. Other objects and advantages will appear in the 30 following specification, in which:

Figure 1 is a perspective view of a toy animal made in accordance with the invention.

Figure 2 is a perspective view of the wire or 35 similar armature.

Figure 3 is a perspective view illustrating the addition of the foundation and other parts to the wire armature of Fig. 2.

Figure 4 is a cross section taken on the line 40 4—4 of Fig. 3.

Figure 5 is a fractional perspective view illustrating how a number of paper or other sheets are fastened together prior to shredding.

Figure 6 is a perspective view illustrating the 45 folding of the foregoing sheets and the ultimate shredding.

Figure 7 is a section taken substantially on the line 1—1 of Fig. 1.

In carrying out the invention the article 1 herein conveniently termed a toy, represents a 50 poodle-dog which is characterized by the long shreds 2 which represent the hair. The nature of this article, which is a toy figure, is most easily understood by defining the elements of its construction from the bottom up, so to speak.

55 In Fig. 2 the armature 3 consists of one or

more wires which have any desired degree of stiffness. This armature comprises a spine portion 4, as well as tail, neck, head and nose portions 5, 6, 7 and 8. Pairs of legs 9 of substantially U or divergently shaped form are centered upon the spine portion 4 in the manner shown, and are there secured by ties 10, which may comprise wire, cord or some other suitable equivalent.

With respect to the foregoing stiffness of the 10 various wires, the nature of the ultimate article 1 will dictate the required type. If the article is of such a kind that it is intended to stand rigidly, then the wires are necessarily much stiffer than if the article is of a kind adapted to 15 be bent into various shapes after it is once finished.

In Fig. 3 a foundation 11 is shown applied to the armature 3 and leg wires 9 thus defining a dome-shaped body. This foundation usually 20 comprises a sheet of cardboard, but it may consist of some equivalent such as stiffened buckram. The remote longitudinal edges of the foundation 11 are secured to the leg wires by tape 12 (Fig. 4). This tape may be of a customary adhesive kind, or it may comprise gummed paper strips. A paper or similar wrapping 13 is applied to those parts of the leg wires which appear below the bottom margins of the foundation. The terminals 14 of the leg 30 wires are doubled over upon themselves (Fig. 1) to provide feet 15.

At this point it is desired to state that the foundation 11 is not necessarily always composed of the materials mentioned. This foundation might comprise a wire or similar network without altering the principle of the invention at this point. The elements 3 to 12 are herein broadly identified as a framework, because it is upon this that the shredded covering is applied 40 in the manner to be described.

Those portions of the armature 3 other than the spine 4 are usually left uncovered. The nose 16 of the toy comprises a heart-shaped paper or similar slip of an appropriate color which is 45 glued at 17 (Fig. 7) to the nose portion 8. Wires 18 (Fig. 3) serve to attach the eyes 19 to the sides of the head portion 7.

The making of the covering is of the most importance because it is this which gives the 50 article its final life-like appearance. Use is made of a plurality of paper or similar sheets 20 (Fig. 5). These are laid upon each other in matching positions and then are stitched at 21 down along the center. The stitching can be 55

substituted by other means of securing the paper sheets along the longitudinal center, the prerequisite being to hold the sheets together in the matching positions shown.

5 The stack of sheets is then folded at 22 (Fig. 6) along the line of stitching. The longitudinal edges of the paper stack should come together along a common margin 23. The paper is then cut at 24 with a scissors or equivalent implement 10 along parallel lines. These cuts are close together and they produce the previously mentioned shreds 2 shown in Fig. 1.

Upon opening the shredded paper stack the latter is applied to the armature 3. The line 15 of stitching 21 comprises a mid-rib, so to speak, a tail following the line of the armature from the tip of the tail portion 5 to the place where the head portion 7 meets the nose 16. The paper covering is secured in any desired way. A 20 line of glue can be run along the foundation 11 directly above the spine portion 4 and extended to the tail, neck and head portions.

The eyes 19 are pulled through convenient ones of the slits or cuts in the paper and after 25 the glue has set the article is shaken to fluff the material. In an actual manufacture of the ar-

5 ticle in the form of the dog shown, the latter has a remarkable life-like appearance even though the materials of manufacture are perfectly common place.

I claim:

10 A toy figure comprising an armature having its approximate ends shaped substantially like the figure parts to be represented, leg members divergently depending from the armature to support the finished figure in a standing position, a foundation applied to the armature and extending over parts of the leg members in a dome-shaped body form, a shredded cover consisting of at least one sheet cut in from opposite 15 margins up to a medial unsevered zone along lines parallel and close to one another, means securing said cover along said zone, centrally of said foundation and toward the ends of the armature, one of the ends being left exposed by said cover, a member attached to said exposed end, and other members attached by wires to the armature contiguously to the first-mentioned member, said wires being pulled through some 20 of the cuts so that the respective members appear outside of the shredded cover.

25 MARION ROSS.
